United States Patent Office.

HENRY W. KETCHAM, OF NEW YORK, N. Y.

Letters Patent No. 86,760, dated February 9, 1869.

IMPROVEMENT IN SAIL-BENDERS.

The Schedule referred to in these Letters Patent and making part of the same.

To all whom it may concern:

Be it known that I, HENRY W. KETCHAM, of the city, county, and State of New York, have invented a new and improved Sail-Bender; and I do hereby declare that the following is a full, clear, and exact description thereof, which will enable others skilled in the art to make and use the same, reference being had to the accompanying drawings, forming part of this specification.

Figure 1 represents my improved sail-bender, attached to a mast-hoop.

Figure 2 is a detail sectional view of the same, taken through the line *x x*, fig. 1.

Similar letters of reference indicate corresponding parts.

My invention has for its object to furnish an improved sail-bender, or detachable metallic seizing, by means of which the sail may be securely attached to the hoop in such a way that it may be securely held, and easily and quickly detached when required; and

It consists in the construction and combination of the various parts, as hereinafter more fully described.

A represents a mast-hoop;

B represents a bolt-rope; and

C, the sail, about the construction of which parts there is nothing new.

D and E are two eye-bolts, which are secured to one side of the hoop A, by nuts, placed upon the ends of said bolts, upon the inner side of the hoop A, as shown in fig. 1.

The bolts D and E are placed at such a distance apart as to receive the bolt-rope B between them freely.

The eye-bolts D and E are of different lengths, and to the eye of the longer one, E, is pivoted or hinged the hook F.

The hook F is made in two parts, which are hinged or jointed to each other, and are made in such a shape as to conform to the form of the bolt-rope and part of the sail attached to said bolt-rope, as shown in fig. 1.

G is a wedge or lock-plate, through an inclined slot

in one end of which passes the shank of the longer eye-bolt E.

In the other end of the plate G is formed a slot, leading upward and inward from the lower edge of said plate, so as to form a hook, which hooks over the shank of the other or shorter eye-bolt D.

In using the bender, the jointed hook, F, is passed through the eyelet of the sail C, around the bolt-rope B, and is hooked into the eye of the shorter eye-bolt D.

The wedge or lock-plate G is then turned and forced down between the bolt-rope B and the hoop A.

As the wedge G is forced down between the bolt-rope B and hoop A, it is forced forward, bringing the shanks of the eye-bolts into the inner ends of the slots in said wedge, securely locking it in place.

In detaching the sail, the wedge G is first pushed back, and can then be raised from its place, releasing the bolt-rope B, and allowing the hook F to be unhooked, detaching the sail.

Having thus described my invention,

I claim as new, and desire to secure by Letters Patent—

1. Securing the bolt-rope of the sail to the hoop, by means of a detachable metallic device, substantially as herein shown and described, and for the purpose set forth.

2. The pivoted slotted lock-plate or wedge G, in combination with the eye-bolts D and E, for the purpose of locking the bolt-rope in place, substantially as herein shown and described.

3. An improved sail-bender, formed by the combination of the eye-bolts D and E, jointed and pivoted hook F, and pivoted wedge or lock-plate G, with each other, substantially as herein shown and described, and for the purposes set forth.

The above specification of my invention signed by me, this 14th day of October 1868.

HENRY W. KETCHAM.
